COMBINATION SINK AND CONSOLE

Jack N. Kaiser, Louisville, Ky., assignor to American Radiator & Standard Sanitary Corporation, New York, N.Y., a corporation of Delaware

Filed Oct. 23, 1965, Ser. No. 87,832

Term of patent 14 years

(Cl. D4—2)

FIG. 1 is a perspective view of a combination sink and console showing my new design, the console and faucet spout being broken away for convenience of illustration only;

FIG. 2 is a front elevational view, the sink and faucet spout being omitted for convenience of illustration; and

FIG. 3 is a side elevational view thereof, the sink being omitted for convenience of illustration.

The dominant features of my design reside in the portions shown in full lines.

I claim:

The ornamental design for a combination sink and console, substantially as shown and described.
